SHAMPOO BOWL

Walter J. Kiefer, Belvidere, Ill., assignor to Belvedere Products Inc., Belvidere, Ill., a corporation of Illinois

Application December 31, 1958, Serial No. 54,007

Term of patent 14 years

(Cl. D4—2)

Fig. 1

Fig. 2

Fig. 3

Fig. 2 is a front elevational view thereof;

Fig. 3 is a side elevational view thereof, the opposite side being a mirror image of Fig. 3; and

Fig. 4 is a rear elevational view thereof.

The dominant features of the design reside in the portions shown in full lines.

I claim:

The ornamental design for a shampoo bowl, substantially as shown and described.
